UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,278,330.

Specification of Letters Patent. Patented Sept. 10, 1918.

Application filed December 2, 1916. Serial No. 134,595.

To all whom it may concern:

Be it known that I, CHARLES L. GOODRUM, a citizen of the United States, residing at New York, in the county of New York and State of New York, have invented certain new and useful Improvements in Telephone-Exchange Systems, of which the following is a full, clear, concise, and exact description.

This invention relates to telephone exchange systems, and more particularly to a system in which a calling subscriber can hold a connection which has been extended to a busy line but cannot establish a talking circuit thereto until said busy line becomes idle.

The object of the invention is to provide means for notifying a called subscriber, whose line has been found busy, that another subscriber is awaiting connection with his line.

The invention is illustrated in the accompanying drawing, which shows diagrammatically a connection between two subscribers, the circuits of a connector switch instrumental in extending such a connection being shown in detail.

In the drawing, the invention is shown associated with a two-wire automatic system, but it will be understood that it may be readily applied to any automatic or semi-automatic system.

In the present embodiment of the invention the called subscriber is notified of a waiting call by putting a tone on his line. It will, however, be seen that those skilled in the art may apply the principle of the invention to operate other notifying means.

In the system illustrated, when the calling subscriber removes his receiver from the hook, the line finder 1, shown diagrammatically, will be switched to his line terminals. Thereupon the subscriber manipulates the finger dial to operate the selector switch 2 in any desired manner to connect his line with the connector switch 15 in the bank of which are the terminals of the called line. When the subscriber's line becomes connected through the selector, a circuit is completed from battery through the right-hand winding of the line relay LR, tip side of the line, subscriber's substation, sleeve side of the line, left-hand winding of relay LR, to ground. The consequent energization of

the relay LR closes an energizing circuit 55 for the slow relay 3, from ground, armature and front contact of relay LR, winding of relay 3, to battery. Relay 3, in pulling up, partially completes a circuit for energizing slow relay 4, which will be described later. 60

The subscriber now sends a second series of impulses, which causes the armature of the relay LR to vibrate. Each time that relay LR is deenergized a circuit is completed from ground, armature and back contact of relay LR, right-hand armature and front contact of relay 3, outermost armature and contact of relay TR, side-switch arm 10 (position 1), through the winding of primary magnet PM, to battery and ground. 70 The magnet PM responding to these impulses steps the wipers of the connector 15 to the group of terminals containing the terminals of the called subscriber.

A circuit for energizing relay 4 is completed in parallel with the circuit just traced from ground, armature and back contact of relay LR, armature and front contact of relay 3, through the winding of the relay 4 to battery. Relay 4 being slow to release 80 remains energized during the sending of each series of impulses, and completes at its inner armature a circuit from ground, left-hand armature and contact of relay 3, inner armature and contact of relay 4, side-switch arm 9 (position 1), through the winding of the side-switch escape magnet Esc., to battery and ground. When the impulses have been sent, the consequent continued energization of the relay LR removes 90 the circuit for holding up relay 4 long enough to allow it to fall back and allow the deenergization of the escape magnet. The side switch, therefore, advances to the second position. 95

The subscriber now sends a third series of impulses, causing the energization of the relay 4, as has just been described, and operating through the second position of the side-switch arm 10 the secondary magnet 100 SM of the connector switch. The magnet SM thus operated steps the wipers of the connector 15 to the terminals of the called line.

When the wipers 15 are connected to the 105 terminals of the called line, the test relay TR will, if the called subscriber's line is busy, which we assume it to be, deenergized

over a circuit leading from ground at the fourth position of the side-switch arm such as 11' of some other line, bottom wiper of another connector such as 15', bottom wiper 5 of the calling connector 15, side-switch arm 11 (position 2), right-hand winding of the relay TR, to battery and ground. The relay TR will complete a locking circuit for itself from ground, left-hand winding of relay 10 TR, innermost armature and contact of relay TR, through conducting portion of the constantly rotating disk 7, to battery and ground. The relay TR will complete a circuit for locking up the escape magnet Esc., 15 from ground at its middle armature and contact, side-switch arm 9 (position 2), winding of escape magnet Esc., to battery and ground. This circuit prevents the advance of the side switch to the third, or 20 ringing position, so long as relay TR is held up.

The purpose of the locking circuit through the left-hand winding of the relay TR is to prevent the connection of more 25 than one calling line at a time to the called line when it becomes idle, for the relay TR can only be deenergized when the called line is idle simultaneously with the passage of an insulated segment 19 of the disk 7 under 30 the contact pen. As these insulated segments are circumferentially spaced on the various disks of a group of connectors so that no two will be under a contact pen at the same time, it is obvious that two lines 35 cannot be so connected simultaneously.

When the relay TR became energized it also completed a circuit for energizing the relay 6 from ground, middle armature and contact of relay TR, side-switch arm 8 (position 2), outer armature and contact of relay 4, through the winding of the relay 6, to battery and ground. The relay 6 in pulling up its armatures closed a circuit from the secondary coil of the transformer 18 through 40 the condenser, left-hand armature and contact of relay 6, side-switch arm 13 (position 2), middle wiper of connector 15, tip side of the line, called subscriber's substation, sleeve side of the line for wiper of connector 45 15, side-switch arm 14 (position 2), right-hand armature and contact of relay 6, to the secondary coil of transformer 18. This circuit, in connection with the tone generator and primary coil of transformer 18, places a 50 tone on the called subscriber's line apprising him of the fact that connection with his line is desired by another subscriber. As here provided, this tone will be continued either until the called subscriber completes his 55 conversation, or until the calling subscriber abandons the call, in which case the restoration of the side switch of the connector will discontinue the tone. If desired the tone 60 may be applied intermittently by means of 65 an interrupter.

A busy-back signal is also provided to the calling subscriber while the side switch is locked in the second position, the connection being made from ground, secondary of the transformer 17, side-switch arm 12 (position 2), off-normal contact ON₁, condenser, tip side of the line, calling subscriber's substation, sleeve side of the line and condenser through the winding of the retardation coil 16, to battery and ground. 75

When the called subscriber hangs up, the energizing circuit through the right-hand winding of the relay TR is broken by the restoration of the side-switch arm 11 of the connector switch which was formerly connected to his line. The next time the insulated segment of the disk 7 passes under the contact pen it will break the locking circuit through the left-hand winding of the relay TR, which will thereupon become deenergized. The locking circuit for the escape magnet is thereby broken at the middle armature of the relay TR, and the escape magnet will, therefore, allow the advance of the side switch into its third position. 90

In this position of the side switch, the escape magnet will be again energized from ground, left-hand armature and contact of relay 3, armature and contact of slow relay 5, side-switch arm 9 (position 3), through the winding of the escape magnet, to battery and ground. The pulling up of the armature of the escape magnet will complete a circuit for ringing the called subscriber from battery, through the winding of the 100 relay 5, armature and contact of escape magnet, side-switch arm 13 (position 3), middle wiper of connector switch 15, tip side of the called line, the ringer of the called line, sleeve side of the called line, top wiper of 105 the connector switch 15, side-switch arm 14 (position 3), to ground. The resistance of the ringer is so high that relay 5, which is low wound, will not energize in series with it. Ringing will continue intermittently until the called subscriber removes his receiver, at which time the shunting of the ringer by his switchhook will reduce the resistance of the circuit sufficiently to allow the energization of the relay 5, which breaks at its armature the energizing circuit of magnet Esc. The magnet Esc. thereupon falls back, advancing the side switch to its fourth position. In this position the talking circuit is complete between the calling and called subscriber, and talking current for the called subscriber is supplied through the retardation coil 16. 110

At the end of the conversation, when the calling subscriber hangs up his receiver he 115 breaks at his switchhook the circuit for holding up the relay LR, which thereupon retracts its armature. In falling back the armature of the relay LR breaks the circuit of the relay 3, which thereupon falls back. 120

125 130

A circuit is thus completed from ground, armature and back contact of the relay LR, armature and back contact of the relay 3, off-normal contact ON₂ through the winding 5 of the release magnet RM, to battery and ground. This causes the restoration of the connector switch. The selector and line-finder will thereupon be restored in the well-known manner.

10 What is claimed is:

1. In a telephone exchange system, the combination with lines leading from a central station to subscribers' stations, automatic means for connecting a calling subscriber's line to a wanted subscriber's line, means for testing the idle or busy condition of a called subscriber's line, and automatic means for notifying a called subscriber when busy that another connection with his 15 line is desired.

2. In a telephone exchange system, the combination with lines leading from a central station to subscribers' substations, means for connecting a calling subscriber's line to 25 a called subscriber's line, means for testing the idle or busy condition of a called subscriber's line, automatic means for notifying a called subscriber when busy, that another connection with his line is desired, means 30 for preventing connection between a calling line and a busy called line, and means for establishing said connection when said called line becomes idle.

3. In a telephone exchange system, subscribers' lines, means including an automatic connector switch for connecting a calling to a called subscriber's line, a side switch associated with said connector switch, actuating means for said side switch, means for testing 35 the idle or busy condition of a called subscriber's line, means actuated when said subscriber's line tests busy for preventing further movement of said side switch during the extent of said busy condition, signaling 40 means operated simultaneously with said preventing means, means at the called subscriber's substation responsive to said signaling means for indicating that another connection is desired, and means for rendering ineffective said preventing means and completing the connection when said called subscriber's line becomes idle.

4. In a telephone exchange system, the

combination with telephone lines, automatic switches for interconnecting said lines, means for testing the idle or busy condition of a called line, means for preventing the completion of a connection between a calling line and a busy called line, means for notifying a busy called subscriber that another 55 connection to his line is desired, and means for rendering ineffective said notifying means whenever the waiting party abandons the call.

5. In a telephone exchange system, the combination with telephone lines, automatic switches for interconnecting said lines, means for testing the idle or busy condition of a called line, means for preventing the completion of a connection to a busy called 60 line, means for producing a tone, and means for connecting said tone producing means to a busy called line when additional connection with said line is desired.

6. In a telephone exchange system, the combination with telephone lines, automatic switches for interconnecting said lines, means for testing the idle or busy condition of a called line, means for preventing the completion of a connection to a busy called 70 line, means for producing a tone, means for connecting said tone producing means to a busy called line when connection with said line is desired by an additional subscriber, and means for discontinuing said tone in 75 case the additional subscriber abandons the call.

7. In a telephone exchange system, a busy line, a plurality of calling lines, means for placing a busy condition on the busy line, means for extending a connection from each calling line to said busy line, means responsive to said busy condition for preventing the completion of the extended connections, means for producing characteristic signals, 80 means responsive to said busy condition for connecting said signal producing means to the busy line, and means operative upon the busy line becoming idle to permit the completion of only one of said extended connections.

In witness whereof, I hereunto subscribe my name this 29th day of November A. D., 1916.

CHARLES L. GOODRUM.
